UNITED STATES PATENT OFFICE.

JOSEPH F. PROSSER, OF CLEVELAND, OHIO, ASSIGNOR TO PROSSER ENGINEERING CO.,
OF CLEVELAND, OHIO, A CORPORATION OF OHIO.

BOTTLE-CAPPING MACHINE.

1,081,466.

Specification of Letters Patent. Patented Dec. 16, 1913.

Application filed June 16, 1913. Serial No. 773,952.

To all whom it may concern:

Be it known that I, JOSEPH F. PROSSER, a citizen of the United States, residing at Cleveland, in the county of Cuyahoga and State of Ohio, have invented certain new and useful Improvements in Bottle-Capping Machines, of which the following is a specification.

This invention relates to improvements in bottle-capping machines of the class for fixing a metallic cap to a bottle, jar, glass, or like receptacle containing food products.

The invention has for its principal object to provide a machine for hermetically sealing such receptacles, so designed that atmospheric pressure will actuate the capping dies, when the operator by means of a foot lever brings the receptacle into proper position with relation to the dies and by the same action closes the vacuum chamber. This is accomplished by employing a valve of special design for controlling the vacuum and atmospheric pressure, which valve is operated from the foot lever simultaneously with the movement of the receptacle to be capped and the closing of the vacuum chamber.

Another object of the invention is to construct a machine of the above class, wherein the vacuum and atmospheric pressure are automatically controlled, thereby providing a smooth working machine and thus preventing breaking of the receptacles during capping, even when an unskilled operator is attending the machine.

With the above and other objects in view as will be understood, the invention will be hereinafter fully described in connection with the accompanying drawings, which illustrate a preferred embodiment thereof, and the novel features of the invention will then be distinctly pointed out in the appended claims.

In the drawings, like characters of reference indicate similar parts.

Figure 1 is a sectional elevation of a machine constructed in accordance with my invention, Fig. 2 is a view illustrating the pressure controlling valve and its connections at a right angle to the same parts in

Fig. 1, Fig. 3 is a longitudinal sectional view, on an enlarged scale, of the pressure controlling valve, and Fig. 4 is a similar view to Fig. 1, the movable parts being shown in a position opposite to that shown in Fig. 1. 55

Referring to the drawings, 1 represents a hollow cylindrical upright stand having a suitable base 2 and an enlarged upper portion 3 which terminates with a circular flange 4. Supported on said flange and fixed thereto by any suitable means, as indicated at 5, is a circular guide plate 6, which has a thickened central depending portion 7, and projecting therefrom is a reduced extension 8. 65

An upright bracket 9, curved in cross section, is fastened to the guide plate at 10 for supporting a cylinder 11, in which is slidably mounted a piston 12. The bottom of the cylinder 11 is raised as indicated at 13, and its under side recessed and threaded at 14 for connecting thereto a vacuum chamber 15 having a reduced open end 16. Communication between the cylinder 11 and the vacuum chamber 15 is established by means of a plurality of ports 17. A finger carrying ring 18 is screwed into the bottom of the cylinder 11 as shown at 19, and to this ring are movably connected in the ordinary manner a plurality of suitable fingers 20 80 having inturned nibs 21 which are beveled on their inner edges as shown at 22. The stem 23 of the piston 12 is slidably mounted in the bottom of the cylinder and in the finger carrying ring 18, and to its protruding end 24 is fixed a suitable die 25 which is adapted to coöperate with the inturned nibs 21 of the fingers 20, for exerting a squeezing pressure on a cap to fix it to a receptacle. The vacuum chamber 15 is 90 preferably provided with a flange opening 26 at its front side, which is closed by a glass 27 to permit observation of the capping action. 85

The means for alternately creating vacuum at one end of the piston and admitting atmospheric pressure at its other end to actuate the same will now be described. The pipe indicated by 28 and leading from a pump or any suitable vac- 95

uum creating means is connected to a controlling valve 29, from which extends a branch pipe 30 connected to the upper end of the cylinder at 31, and another branch pipe 32 leads from the valve to the lower end of the cylinder. The bracket 9 being cut out at 33 to permit the connection of the branch pipe 32 to the cylinder as shown at 34. The controlling valve 29 is so designed that its plug 35 which is cut away at 36 and 37, when turned counter clockwise, will begin to open the passage 38 leading to the vacuum pipe 28, thereby establishing communication between the vacuum pump and the lower end of the cylinder by way of the passage 39, before it begins to uncover the air inlet 40, and thus admit atmospheric pressure through the passage 41 to the upper end of the cylinder to force the piston downwardly. It will be noted that the plug 35 will close the passage 39 thereby breaking the vacuum, just before the passage 41 is closed and the atmospheric pressure cut off. This will leave an air cushion below the piston, which will prevent sudden movement thereof at the end of its stroke. While the plug 35 is still turning in the same direction, it will begin to open the passage 41 to establish communication between the vacuum pump and the upper end of the cylinder, before the passage 39 begins to be uncovered and thus admit atmospheric pressure to the lower end of the cylinder for driving the piston upwardly. Again, it is to be noted that the passage 38 is closed in advance of the air inlet 40, whereby the vacuum at the upper end of the cylinder will be broken before the atmospheric pressure is cut off to its lower end, thereby leaving an air cushion above the piston.

The mechanism for supporting the receptacle to be capped and closing the vacuum chamber 15 consists of a circular table 42, which is fixed to the upper end of a tube 43 as at 44. Said tube is slidably mounted in the guide plate 6, in vertical alinement with the stem 23 of the piston 12, and a recess or pocket 45 is provided in said guide plate for receiving the table 42 when in its down position. The table 42 is hollowed out at 46, and resiliently mounted therein is a platform 47 for carrying the receptacle to be capped. Said table 42 is adapted to be brought into engagement with the reduced open end 16 of the vacuum chamber 15 for closing the same, and in order to obtain a tight joint, the table is provided with an annular groove for holding a rubber ring 48 which will butt against the end of the vacuum chamber. Slidably mounted in the lower end of the tube 43 is a rod 49, and interposed between the upper end of the same and the threaded portion

44 of the table is a spring 50. A member 51 is fixed to the lower end of the rod 49, to which is pivoted at 52 a connecting rod 53 whose other end is pivotally connected at 54 to a foot lever 55. The base 2 of the stand 1 is slotted as shown at 56 for receiving said foot lever, which is pivoted at 57 between spaced lugs projecting from the base. The outer free end of the foot lever is provided with a pedal 58. When the foot lever 55 is actuated by pressure on the pedal 58 it is obvious that the table 42 will be raised into engagement with the lower open end of the vacuum chamber 15. In order that the pressure controlling valve 29 may be operated as already described at the same time that the vacuum chamber is closed by the table 42, a lever 59 is fixed to the stem 60 of the pressure valve, and to this lever is pivoted at 61 a connecting bar 62. The connecting bar is preferably offset as shown at 63 for clearing the pipe 32, and its lower end passes through an opening 64 in the guide plate 6 and is pivoted at 65 to the free end of a lever bar 66, which is pivotally connected at 67 between a pair of lugs extending laterally from the part 8 of the guide table 6. An elongated opening 68 is provided in the upper portion 3 of the stand 2 for receiving the lever bar 66. Said lever bar is actuated upwardly on its pivot 67 by means of a push rod 69, which is pivoted thereto at 70 and carries an adjustable stop 71 which is so fixed to the rod, that the arm 72 extending from the member 51 will engage said stop to actuate the lever bar and thereby operate the pressure valve 29.

The operation follows: Assuming a receptacle 73 to which the metallic cap 74 is to be fixed has been placed on the table platform 47 and the parts of the machine are as shown in Fig. 1. The operator presses on the pedal 58, thereby forcing the rod 49 upwardly, which acting upon the spring 50 causes the table 42 to be lifted into engagement with the open end of the vacuum chamber 15 and also bring the metallic cap 74 on the receptacle into proper position for the squeezing action of the die 25 thereon as shown in Fig. 4. At the moment the table 42 closes the vacuum chamber, the arm 72 engages the stop 71 and the push rod 69 will move the lever bar 66, whereby the pressure valve lever 59, through the connecting bar 62, will turn the valve plug 35 counter clockwise. A vacuum will be created at the lower end of the piston 12 and also within the vacuum chamber 15, and atmospheric pressure admitted to the other end of the piston as heretofore explained, for forcing the piston downwardly and causing the die 25 to act upon the metallic cap 74. As the valve plug 35 is still being turned in the same direction through the action of foot lever, a vacuum

is created at the upper end of the piston and atmospheric pressure admitted to the lower end thereof, whereby the piston will be driven upwardly, the vacuum in the chamber 5 15 broken, and if the operator releases the pedal 58, the table 42 will drop within its pocket 45, the arm 72, will fall away from the stop 71 thus permitting the lever bar 66 to drop and by pulling on the connecting bar 10 62 the plug of the pressure controlling valve 29 will be returned to its original position.

It will be understood that slight changes in the details of construction and arrangement of the parts may be resorted to within 15 the scope of the claims.

Having fully described my invention, what I claim is:

1. In a bottle-capping machine, the combination of a cylinder, a piston in the cylinder, capping means actuated by the piston, means for admitting pressure to the cylinder for reciprocating the piston, means for moving a receptacle into position for being capped, and means for controlling the means 20 25 for admitting pressure to the cylinder from the last mentioned means, substantially as described.

2. In a bottle-capping machine, the combination of a cylinder, a piston in the cylinder, capping means actuated by the piston, a valve for controlling a vacuum at one end of the piston and admitting pressure at the other, a table for supporting a receptacle, means for moving the table to bring the receptacle into position for being capped, and means for operating said valve from the movement of the table, substantially as described.

3. In a bottle-capping machine, the combination of a cylinder, a piston in the cylinder, capping means actuated by the piston, a vacuum chamber inclosing the capping means and having an open end, means for establishing communication between one 40 45 end of the cylinder and the vacuum chamber, a valve for controlling a vacuum at one end of the piston and admitting pressure at the other, a movable table for supporting a receptacle, means for moving the table to close the open end of the vacuum chamber and to bring the receptacle into position for being capped, and means for operating said valve from the movement of said table, substantially as described.

5. In a bottle-capping machine, the combination of a cylinder, a piston in the cylinder, capping means actuated by the piston, a vacuum chamber inclosing the capping means, and having an open end, means for 50 60 establishing communication between one end of the cylinder and the vacuum chamber, a valve for controlling a vacuum at one end of the piston and admitting pressure at the other, a table for supporting a receptacle, the table being fixed to a slidably

mounted tube, a rod slidably mounted in the tube, a spring within the tube for resiliently supporting the same on the rod, means for moving said rod to move the table against the open end of the vacuum chamber and bring the receptacle into position to be capped, and means for operating said valve from the movement of said rod after the closing of the vacuum chamber, substantially as described. 70 75

5. In a bottle-capping machine, the combination of a cylinder, a piston in the cylinder, capping means actuated by the piston, a vacuum chamber inclosing the capping means, and having an open end, means for establishing communication between one end of the cylinder and the vacuum chamber, a valve for controlling a vacuum at one end of the piston and admitting pressure at the other, a table for supporting a receptacle, the table being fixed to a slidably mounted tube, a rod slidably mounted in the tube, a spring within the tube for resiliently supporting the same on the rod, means for moving said rod to move the table against the open end of the vacuum chamber and bring the receptacle into position to be capped, 80 85 90 95 100

10. In a bottle-capping machine, the combination of a stand, a cylinder arranged above the stand, a piston in the cylinder, capping means below the cylinder and actuated by the piston, a vacuum chamber depending from the bottom of the cylinder and having a lower open end, the bottom of the cylinder being provided with ports leading into the vacuum chamber, a valve for controlling a vacuum at one end of the piston and admitting atmospheric pressure at its other end, a movable table for supporting a receptacle and adapted to close the open end of the vacuum chamber, the table 105 110 115 being fixed to a tube, the tube being slidably mounted in the stand, a rod slidably mounted in the tube, a spring within the tube for resiliently supporting the same on the rod, means for moving said rod to move the table against the open end of the vacuum chamber and bring the receptacle into position to be capped, and means for operating said valve from the movement of said rod after the closing of the vacuum chamber, 120 125 substantially as described.

7. In a bottle-capping machine, the combination of a cylinder, a piston in the cylinder, capping means actuated by the piston, a valve for cutting off a vacuum creating 130

means at one end of the piston before pressure is admitted at its other end, a table for supporting a receptacle, means for moving the table to bring the receptacle into position for being capped, and means for operating said valve from the movement of the table, substantially as described.

In testimony whereof I affix my signature in presence of two witnesses.

JOSEPH F. PROSSER.
